DESIGN FOR A FISH LURE

Samuel Jorgensen, Fresno, Calif.

Application May 30, 1944, Serial No. 113,805

Term of patent 14 years

(Cl. D31—4)

To all whom it may concern:

Be it known that I, Samuel Jorgensen, a citizen of the United States, and residing on Route 3, Box 579, Fresno, California, have invented a new, original, and ornamental Design for Fish Lures, of which the following is a specification, reference being had to the accompanying drawing, forming part thereof.

Fig. 1 is a front elevational view of the fish lure, showing my new design.

Fig. 2 is a side elevational view.

Fig. 3 is a vertical sectional view taken on lines 3—3 in Fig. 1, and

Fig. 4 is a cross sectional view taken on line 4—4 in Fig. 2.

I claim:

The ornamental design for a fish lure, as shown.

SAMUEL JORGENSEN.
